UNITED STATES PATENT OFFICE.

JOHN FERNSLER, OF PHILADELPHIA, PENNSYLVANIA.

DESIGN FOR A BARBER'S SANITARY CABINET.

45,747.

Specification for Design.

Patented May 12, 1914.

Application filed March 18, 1914. Serial No. 825,696. Term of patent 7 years.

To all whom it may concern:

Be it known that I, JOHN FERNSLER, a citizen of the United States, residing at Philadelphia, in the county of Philadelphia and State of Pennsylvania, have invented a new, original, and ornamental Design for Barbers' Sanitary Cabinets, of which the following is a specification, reference being had to the accompanying drawing, forming a part thereof.

The figure is a perspective view of a barber's sanitary cabinet showing my new design.

I claim:

The ornamental design for a barber's sanitary cabinet, as shown.

JOHN FERNSLER.
